ADVERTISING DEVICE

Huot Walter Sternberg, Westport, Conn., assignor
to The Owen Silent Spring Company, Inc.,
Bridgeport, Conn., a corporation of Connecti-
cut

Application February 7, 1939, Serial No. 255,035

10 Claims. (Cl. 40—125)

This invention relates to an advertising display device and more particularly to one of the roller shade type.

One of the objects of this invention is to provide an advertising device of the roller shade type in which the support for the roller shade is held in position by the article which is advertised.

A more specific object of this invention is to produce an advertising device of this character for advertising mattresses and the like which includes a support into which the mattresses may be inserted so that the weight of the mattress and the shape of the mattress may be utilized to hold the support in position to properly align the shade roller advertising sheet when it is unwound and drawn across the mattress.

Another object of this invention is to provide means whereby the support may be folded for ease in shipping.

Another object of this invention is to provide means for clamping the support to the article to be advertised.

Another object of this invention is to provide the support with an extension which simulates the head end of a bed and which provides means for supporting a display card or sheet.

Other objects of this invention will appear from the following description taken in connection with the drawing, in which—

Fig. 1 shows a preferred form of my invention in assembled relation with a mattress and in which the sheet upon which the advertising matter appears is in displaying position on the mattress;

Fig. 2 is a perspective view of the device shown in Fig. 1, partly broken away, with the advertising sheet in rolled-up position;

Fig. 3 is a perspective view of a modified form of support;

Fig. 4 is a perspective view of another modified form of support;

Fig. 5 is a vertical sectional view on the line 5—5 of the modification in Fig. 4; and

Fig. 6 is a perspective view of another modified form of support.

For the purpose of disclosure, I have shown my invention used for advertising a mattress disclosed in perspective in Fig. 1 by the reference character 9. The mattress may be supported on any suitable support 10 such as a platform or bed spring or on a bed if desired. The advertising display device comprises a sheet of material 11 upon which any suitable advertising

matter may be imprinted, such as the design of the interior spring construction of the mattress and any other special features to which it is desired to call the prospective purchaser's attention. This sheet is made of any suitable material such as shade material or the like which may be supported on a roller 12 which may be the usual spring type shade roller so that the sheet may be readily rolled up on the roller when it is desired to display the top of the 10 mattress.

As a means for supporting the roller in proper relation to the mattress, I have provided a support 14, Figs. 1 and 2, which comprises a base 15 and upstanding right triangular members 16 and 17 on the ends of the base upon which the ends of the roller may, if desired, be supported by means of well-known shade roller supporting brackets 18, one of which is indicated on the member 16, Fig. 2. On the rear edge of the base 15 is an upstanding member 19 which may be integral with the base and members 16 and 17, if desired, and integrally connected to the upper end of the upstanding member 19 is a forwardly projecting hood member 20 which projects over the roller to substantially conceal the same. This member may also be integral with the upstanding members 16 and 17 or the various members 15, 16, 17, 19 and 20 may be made of separate pieces connected together in any suitable manner. The members 16 and 17 are extended at right angles to the base 15 and at right angles to the member 19 which also extends at right angles to the base 15 and the members 16 and 17 are spaced to receive the end of the mattress as shown in Fig. 1 whereby when the mattress when positioned as in Fig. 1 will hold the support securely in position against movement towards the projecting end of the mattress as the shade is drawn over the mattress as shown in Fig. 1 and also cause the sheet 11 to align with the mattress when it is drawn over the mattress as shown in Fig. 1. If desired, one or both of the members 16 and 17 may be provided with hooks 21 upon which swatches of mattress material may be supported.

In Fig. 3 I have disclosed a modified construction in which material has been cut away from the base 15a and the end members 16a and 17a to provide a lighter construction and the rear upstanding member 19a has been extended upwardly to simulate the head end of a bed which may support a display card 22 inserted between 55

the shade roller and the member 19a, and resting on the base 15a as indicated.

In the modification shown in Figs. 4 and 5, provision is made for folding the support for easy shipment. In this modification the base 15b is provided with an upstanding member 24 to which is hinged as by any suitable hinge construction 25, a member 26 provided with forwardly extending end flanges 16b and 17b to which brackets, not shown, supporting the roller 12 are secured. The member 26 may be extended forwardly to provide a hood member 20a, corresponding to the hood member 20 in Fig. 2. For the purpose of holding the member 26 in vertical position and also for holding the support against lateral movement with respect to the mattress, each end of the member 26 is preferably connected by suitable linkage connections to ends of the base 15b, the linkage connections comprising links 27 and 28 pivotally connected as indicated to the members 15b and 26 and connected together by a break hinge construction as indicated at 29. When it is desired to ship the support, the support may be folded 25 as indicated by the dotted lines in Fig. 5.

In Fig. 6 I have shown another construction in which the base 15c consists of a narrow strip of material provided at its ends with upstanding members 16c and 17c which support a shade roller as indicated, the support 17c being provided with the usual circular opening rotatably receiving the trunnion fixed in one end of the shade roller and the support 16c being provided with a conventional form of interrupted non-circular locking opening 30 cooperating with the trunnion at the other end rotatably mounted in it and to which and the roller the roller spring is connected. Those details have not been shown as they are old and well-known. The members 16c and 17c are preferably connected together at their upper ends by a bar 31 and all of the members 15c, 16c, 17c and 31 may be made from a continuous bar. For the purpose of holding the support in position on the mattress I provide the support with a clamping bar 32 the ends of which may be turned downwardly as indicated at 33 and 34 to slidably engage the members 16c and 17c and in which are mounted threaded studs 35 and 36 projecting through slots 37 and 38 in the members 16c and 17c whereby the clamping member 32 may be raised before the mattress is laid on the base 15c and then lowered into clamping engagement with the mattress in which position it may be clamped by means of thumb nuts 39 and 40. This provides a very much lighter construction than the other modifications described, at the same time providing means whereby the shade roller will be held against movement in the direction of the length of the mattress and in 60 angular relation thereto when the advertising sheet 11 is drawn over the mattress as indicated in Fig. 1.

While I have described several constructions made according to the principles of my invention, it is to be understood that I reserve the right to make all such other changes as fall within the principles of the invention disclosed and herein-after set forth in the claims.

I claim:

1. An advertising device comprising an advertising sheet, a roller therefor, and a support for said roller comprising a horizontal base upon which an end of an article to be advertised may be placed, an upstanding member for cooperating 75 with the edge of said end of said article and

forwardly extending flanges on said member on which said roller is journaled, said member consisting of two sections hinged together along a horizontal line, the upper section supporting said flanges and the lower section being connected to said base and of a height equal to the width of said flanges. 5

2. An advertising device comprising an advertising sheet, a roller therefor, a support for said roller comprising a horizontal base upon which 10 an end of an article to be advertised may be placed, an upstanding member for cooperating with the edge of said end of said article, forwardly extending flanges on said member on which said roller is journaled, said member consisting of two sections hinged together, the upper section supporting said flanges and the lower section being connected to said base and of a height equal to the width of said flanges, and linkage connections between said base and said 20 upper section of said upstanding member and located near the side edges thereof to receive and cooperate with the side edges of said article. 25

3. An advertising device comprising an advertising sheet, a roller therefor, a support in the 25 form of a rectangular frame comprising a base upon which an article to be advertised may be supported, end members in which said roller is journaled and a top member connecting said end members, a clamping member extending between 30 said end members and adapted to be moved into and out of engagement with said article, and means for slidably supporting said clamping member on said end members and for locking the same thereto. 35

4. An advertising device comprising an advertising sheet, a roller therefor, a support in the form of a rectangular frame comprising a base upon which an article to be advertised may be supported, end members in which said roller is 40 journaled and a top member connecting said end members, a clamping member extending between said end members and adapted to be moved into and out of engagement with said article, and means for slidably supporting said clamping 45 member on said end members and for locking the same thereto, said end members being spaced to cooperate with the side edges of said article.

5. The combination with an article of substantially rectangular cross section, of an advertising 50 device comprising a sheet bearing advertising matter, a roller upon which said sheet may be wound and from which it may be unwound, a support for the roller comprising a base upon which one end of the article is placed to support 55 the base in position, and means on said base supporting said roller above said end of said article, said sheet when unwound being adapted to overlie said article.

6. The combination with an article of substantially rectangular cross section, of an advertising 60 device comprising a sheet bearing advertising matter, a roller upon which said sheet may be wound and from which it may be unwound, a support for the roller comprising a base upon 6 which the end of the article is placed, and means on the base enclosing said end of the article and cooperating therewith to support said roller for movement of said sheet along the length of said article.

7. The combination with an article of substantially rectangular cross section of an advertising device comprising a sheet bearing advertising matter, a roller upon which said sheet may be wound and from which it may be unwound, and

5 a support for said roller comprising a horizontal base for supporting one end of the article and vertical members cooperating with the sides of the article to aline said sheet with the article as the sheet is drawn over the article.

8. The combination with an article of substantially rectangular cross section, of an advertising device comprising a sheet bearing advertising matter, a roller upon which said sheet may be wound and from which it may be unwound, and a support for said roller comprising a horizontal base supporting one end of the article, upstanding members cooperating with the sides of said article on which said roller is journaled and an upstanding member on said base for cooperating with the adjacent end edge of the article, to aline said sheet with said article as said sheet is drawn over said article.

9. The combination with an article of substantially rectangular cross section, of an advertising device comprising a sheet bearing advertising matter, a roller upon which said sheet may be wound and from which it may be unwound, and a support for said roller comprising a horizontal base supporting one end of the article, upstanding members cooperating with the sides of said article

and on which said roller is journaled and an upstanding member on said base for cooperating with the adjacent end edge of the article, to aline said sheet with said article as said sheet is drawn over said article, and a hood member projecting forward and from said latter upstanding member over said roller.

10. The combination with an article of substantially rectangular cross section, of an advertising device comprising a sheet bearing advertising matter, a roller upon which said sheet may be wound and from which it may be unwound, and a support for said roller comprising a horizontal base supporting one end of the article, upstanding members cooperating with the sides of said article and on which said roller is journaled and an upstanding member on said base for cooperating with the adjacent end edge of the article, to aline said sheet with said article as said sheet is drawn over said article, and a hood member projecting forward and from said latter upstanding member over said roller, said base and all of said members being connected together at their adjacent edges.

HUOT WALTER STERNBERG.
